UNITED STATES PATENT OFFICE.

FREDERICK G. ALLEN, OF ERIE, PENNSYLVANIA.

ELECTRICAL CONNECTING DEVICE.

1,208,074.

Specification of Letters Patent. Patented Dec. 12, 1916.

Application filed November 3, 1915. Serial No. 59,358.

To all whom it may concern:

Be it known that I, FREDERICK G. ALLEN, a citizen of the United States, residing at Erie, in the county of Erie and State of Pennsylvania, have invented a new and useful Improvement in Electrical Connecting Devices, of which the following is a specification.

This invention relates to improvements in electrical connecting devices of the plug and socket type, and more particularly to that part of a connecting device of this kind which is adapted to be inserted into a socket or outlet.

The objects of the invention are to provide a plug of improved construction for a connecting device of this kind which can be inserted endwise into a lamp socket or outlet and locked in place therein by turning the plug relatively to the socket through a partial revolution; also to improve the construction of electrical connecting devices of this kind in the respects hereinafter specified.

In the accompanying drawings: Figure 1 is an elevation of a connecting device having an attachment plug embodying the invention. Fig. 2 is a longitudinal sectional elevation thereof on an enlarged scale. Figs. 3 and 4 are transverse sectional views of the attachment plug on line 3—3, Fig. 2, showing the parts of the plug in different positions. Fig. 5 is a transverse sectional view thereof on line 5—5, Fig. 2. Fig. 6 is an end view thereof. Fig. 7 is an elevation thereof on the same scale as Fig. 1, showing the parts in different positions. Fig. 8 is a perspective view of a retaining ring of the plug. Fig. 9 is a fragmentary sectional view of the retaining ring, showing the means for locking the ends of the ring. Figs. 10 and 11 are fragmentary vertical sections of the plug, showing the manner in which the central contact piece is secured thereto. Fig. 12 is an elevation of an electric lamp having a connecting plug of modified construction. Fig. 13 is a central sectional elevation of the plug, on an enlarged scale. Figs. 14 and 15 are transverse sections thereof on line 14—14, Fig. 13, showing the parts of the plug in different positions. Fig. 16 is an end view thereof. Fig. 17 is a sectional elevation of the split shell of the plug, on the same scale as Fig. 12. Fig. 18 is an elevation of the eccentric shell or member of the plug.

Referring to the construction shown in Figs. 1-11, A represents a socket or outlet of the kind commonly used and which has an internally threaded part a adapted to engage with a correspondingly threaded part of a plug, and a central contact member a' with which a part of the plug is adapted to engage. The socket may be of any usual or suitable construction and of itself constitutes no part of this invention. The plug comprises the usual core or insulating body portion B which may be made of porcelain or other suitable insulating material and which is formed with the usual holes or passages for the conductors which are connected to the attachment plug. A conductor b passes through a hole b' terminating at one end in the contact end of the insulating member, and a conductor b² passes into a hole b³ terminating at one end in the side of the insulating member. Both holes b' and b³ converge and form an enlarged passage b⁴ terminating in one end of the plug. The core is preferably provided with the usual knurled portion b⁵ which facilitates the handling of the same. The peripheral portion of the insulating core or member has a plurality of eccentric or cam faces C, three being provided in the construction shown. D represents a split or expandable contact member, ring or shell having inwardly projecting bearing members or parts d adapted to engage the cam faces to cause the split shell to expand or contract. The insulating member is also provided on its periphery with grooves or depressions e which are arranged between the eccentric faces, and into which the bearing members d are adapted to enter when the split sleeve is contracted. The split sleeve is preferably provided with screw threads d' which are similar to those provided on the usual Edison type of lamp base and which fit lamp sockets and outlets of the kind in common use. Means of any suitable construction may be employed for holding the split sleeve against endwise movement thereof relatively to the plug, those shown comprising a retaining ring or collar E secured in a shallow annular groove e formed on the contact end of the insulating member or core, and having an outwardly extending flange e' which is adapted to engage with an inwardly extending flange of the split shell. The two flanges e' and e² are preferably provided with radial slits e³ which prevent the flanges from stiffening

the collar E and the split shell D to such an extent as to prevent the expansion and contraction of the collar and sleeve. The collar E is preferably split so that it can be readily removed from or placed on the insulating member and is provided with any suitable means for connecting the ends of the collar, the means shown comprising a lip or projection e^4 which is punched out of the 5 collar near one end thereof, and which is adapted to engage in a hole or recess e^5 in the other end of the collar. The collar E is made of conducting material and is provided with an arm F which extends into the 10 hole b^2 . The end of the arm F is provided with suitable connecting means, such as a binding screw f engaging in a threaded hole in the arm F and by means of which the conductor b^2 is electrically connected with 15 the collar E. Any other means for electrically connecting the split shell with a conductor may be employed. The split sleeve is preferably also provided with means for limiting the turning of the sleeve 20 relatively to the insulating member, so that the bearing members of the split sleeve will not move beyond the circumferential length of the cam faces. In the construction shown for this purpose one of the bearing members d is provided with a hook-shaped extension G which projects into a circumferential slot or groove g in the body portion of the plug and which engages the ends of the groove to limit the turning of the shell. 25 One end of this groove registers with one of the grooves c through which the extension G can be passed when the split shell is being placed into its operative position in assembling the parts of the plug. The passage b^3 and the split shell D are preferably so arranged relatively to each other that when the shell is in its maximum expanded position, the slit or opening therein will be in registration with the passage b^3 , as shown 30 in Fig. 7, so that the conductor b^2 can be connected with the arm F without making it necessary to dismantle the plug. If desired, however, the split collar E can be removed, thus withdrawing the arm F from 35 the passage b^3 and by passing the conductor b^2 through the passage b^3 the conductor can be connected with the arm while the same is removed from the passage b^3 . The contact 40 end of the attachment plug is provided with the usual central contact piece which is adapted to make contact with one of the terminals of a socket when the plug is in place 45 therein. The central contact piece may be of any suitable construction, but preferably 50 consists of a metal strip H, the ends of which are bent to enter into undercut notches h in the plug, and which has a threaded hole adapted to receive a connecting screw h' by means of which the conductor b may be secured to the contact 55 piece. The contact piece when placed on the plug is first arch-shaped as indicated in Fig. 10, so that the ends thereof can be inserted into the notches h , and is then pressed into the shape shown in Fig. 11 in which the ends of the contact piece are forced into the notches to hold the contact piece rigidly in place on the plug. 60

In the use of the connecting device the attachment plug is inserted endwise into a 70 socket or outlet as far as possible, the threads of the split shell slipping over the threads in the socket. When the plug has been pushed into the socket as far as possible, the plug is turned through a part of 75 a revolution, which first causes the threads of the split shell to move into proper relation to the threads in the socket or outlet and then causes the bearing members d to engage the cam faces to cause the split shell 80 to be expanded and pressed against the threaded part of the socket, thus forming a good contact between these two parts. The turning of the plug also causes the central 85 contact piece to be pressed into engagement with the corresponding part of the socket, and causes the two flanges e^4 e^5 to be pressed into contact, so that good contacts are insured at all points at which the circuit is completed by contacting parts. 90

In Figs. 12-18 inclusive, a lamp is shown having at its base an attachment plug of somewhat modified construction. In this construction I represents the glass bulb of a lamp in which the usual filament (not shown) is suspended, which is electrically connected with two wires or conductors i i' . The conductors are embedded in the glass at the base of the lamp and one conductor i is connected to a central contact piece i^2 of 95 the usual kind. A sleeve or shell K is rigidly secured to the glass of the base of the lamp and forms therewith the body portion or core of the connecting device. The shell is electrically connected with the other contact 100 i' , and has cam-shaped or eccentric faces k and depressions k' arranged between the eccentric faces. The shell is provided at its inner end with a flange k^2 and at its outer end with an annular groove k^3 and with a 105 flange k^4 . A threaded split shell L is arranged between the flanges k^2 and k^4 and is held thereby against endwise movement. The split shell L is provided with bearing 110 members l secured on the inner face of the shell and adapted to engage with the eccentric faces k . The split shell is preferably provided with an inwardly extending flange l' which enters the groove k^3 and which has an upwardly bent lip or projection l^2 which extends into a recess l^3 in the flange k^4 and which limits the movement 115 of the split shell relatively to the fixed shell to prevent the bearing members from moving through a distance greater than the 120 125 130

length of the cam faces. In the construction of this connecting device, the fixed shell is made with its outer flange *k* extending substantially parallel with the body portion 5 thereof as shown in full lines in Fig. 18, and after the split member has been placed into its operative position on the fixed shell, this flange is turned over into the position shown in dotted lines in Fig. 18, thus holding 10 the split member in place on the fixed member of the base. In the use of this connecting device the lamp base or plug is inserted into the socket until the central contact member engages the contact in the 15 socket and the lamp is then turned through a part of the revolution to cause the cam faces to expand the split shell. The bearing members *l* press against the cam faces of the sleeve *K* and are pressed against the 20 threaded part of the socket so that a good contact is insured between these three parts.

The attachment plug described has the advantage that it can be readily applied to a socket or outlet by merely pushing the 25 plug into the socket or outlet and turning the same through a part of a revolution, which secures the plug rigidly in place and presses the contacting parts into engagement so that the resistance to the flow of an 30 electric current through the contacting faces is reduced to a minimum.

I claim as my invention:

1. In an electrical connecting device, a plug adapted to be inserted into a socket 35 and comprising a core, and an expansible shell surrounding said core, said core and shell having parts which operate by relative rotation of the core and shell to expand the shell into holding engagement with the 40 socket.

2. In an electrical connecting device, a plug adapted to be inserted into a socket and comprising a core, and an expansible shell surrounding said core and having parts 45 adapted to engage parts in the socket for retaining the plug in the socket, said core having eccentric faces adapted by turning the core relatively to the shell to expand the shell into holding engagement with the 50 socket.

3. The combination with a socket, of a plug adapted to be inserted into the socket and comprising a core, an expansible shell surrounding said core, and parts on said 55 shell and core which operate by relative rotation of the core and shell to expand the shell into holding engagement with the socket.

4. A plug for socket and plug electrical 60 connectors comprising a core, a screw-threaded expansible shell surrounding said core and adapted to enter said socket endwise when contracted and to yieldingly engage with screwthreads in the socket, and 65 parts on said shell and core which operate

by relative rotation of the core and shell to expand the shell into holding engagement with said socket.

5. The combination with a socket having an internally screwthreaded part, of a plug 70 adapted to be inserted into said socket and comprising a core, and an expansible screw-threaded shell surrounding said core and adapted to enter said screwthreaded socket endwise when contracted, said core and shell 75 having parts which operate by relative rotation of the core and shell to expand the shell for causing the threads of the shell and socket to be pressed into holding engagement.

6. In an electrical connecting device, a plug adapted to be inserted into a socket and comprising a core having a cam face, and an expansible shell having a part 80 engaging said cam face and a part adapted to frictionally engage said socket when inserted endwise into the socket and being pressed into holding engagement with the socket by said cam face when said core is turned.

7. The combination with a socket having an internally screwthreaded part, of a plug 85 adapted to be inserted into said socket and comprising a core having a cam face, and an expansible screwthreaded shell surrounding said core and adapted to be inserted endwise into said socket when contracted, said shell having a part engaging 90 said cam face and being expanded by relative rotation of the core and shell to press the threads of the shell and socket into holding engagement.

8. The combination with a socket, of a plug comprising a core having a cam face, and an expansible shell surrounding said 100 core and having a part adapted to engage said cam face and parts adapted to cooperate with parts of the socket for holding the plug in the socket, said plug being adapted to be moved endwise into the 110 socket when the shell is contracted and to be secured in the socket by relative rotation of the core and shell which causes the shell to expand and the parts of the shell and socket to be pressed into holding engagement.

9. In an electrical connecting device, a plug adapted to be inserted into a socket and comprising a core, an expansible shell surrounding the core, said core and shell 120 having parts which operate by relative rotation of the core and shell to expand the shell into holding engagement with the socket, and means for preventing endwise movement of said shell relative to said core.

10. In an electrical connecting device, a plug adapted to be inserted into a socket and comprising a core, an expansible shell surrounding the core, said core and shell having parts which operate by relative ro- 130

tation of the core and shell to expand the shell into holding engagement with the socket, and a collar adapted to engage the shell to limit the endwise movement thereof 5 and to permit electric current to flow from the shell to the collar.

11. In an electrical connecting device, a plug adapted to be inserted into a socket and comprising a core of insulating material having passages for conductors, an expansible shell surrounding the core, said core and shell having parts which operate by relative rotation of the core and shell to expand the shell into holding engagement 15 with the socket, and a collar secured to said core and having a part extending into one of said passages and connected with a conductor, said collar engaging with said shell to limit the endwise movement of the shell 20 and to form an electrical connection therewith.

12. In an electrical connecting device, a plug adapted to be inserted into a socket and comprising a core of insulating material having passages for conductors, an expansible shell surrounding the core, said core and shell having parts which operate by relative rotation of the core and shell to expand the shell into holding engagement 25 with the socket, and a collar removably secured on said core and adapted to engage said shell to limit the endwise movement thereof.

13. In an electrical connecting device, a plug adapted to be inserted into a socket and comprising a core, an expansible shell surrounding the core, said core and shell having parts which operate by relative rotation of the core and shell to expand the shell into holding engagement with the socket, a collar secured on said core, and cooperating parts on said collar and said shell which prevent endwise movement of the shell.

14. In an electrical connecting device, a plug adapted to be inserted into a socket and comprising a core of insulating material having passages for conductors, one of said passages terminating in a side of the core, and an expansible split shell surrounding said core, said core and shell having parts which operate by relative rotation of the core and shell to expand the shell into holding engagement with the socket, said shell having an opening adapted to register with the end of the passage which terminates in a side of the core.

15. In an electrical connecting device, a plug adapted to be inserted into a socket and comprising a core of insulating material having passages for conductors, one of said passages terminating in a side of the core, an expansible split shell surrounding said core, said core and shell having parts which operate by relative rotation of the

core and shell to expand the shell into holding engagement with the socket, a collar secured on said shell for limiting the endwise movement of said shell and making an electrical contact therewith, said collar having 70 an arm extending into the passage in the side of the core and connected with a conductor, said shell having an opening adapted to register with the end of said passage to afford access to said arm.

16. In an electrical connecting device, a plug adapted to be inserted into a socket and comprising a core, an expansible shell surrounding the core, said core and shell having parts which operate by relative rotation of the core and shell to expand the shell into holding engagement with the socket, means for preventing endwise movement of said shell relative to said core, and means for limiting the rotation of said shell 80 relative to said core.

17. In an electrical connecting device, a plug adapted to be inserted into a socket and comprising a core having a cam face, an expansible shell having a part engaging said cam face and being adapted to be expanded by relative rotation of the core and shell to press the shell into holding engagement with the socket, and means on said core and said shell for limiting the relative rotary 95 movement of said shell and core.

18. In an electrical connecting device, a plug adapted to be inserted into a socket and comprising a core having a cam face, an expansible shell having a part engaging 100 said cam face and being adapted to be expanded by relative rotation of the core and shell to press the shell into holding engagement with the socket, stops on the core, and a projection on said shell adapted to engage 105 said stops for limiting the relative rotary movement of said shell and core.

19. In an electrical connecting device, a plug adapted to be inserted into a socket and comprising a core having a cam face, 110 an expansible shell having a part engaging said cam face and being adapted to be expanded by relative rotation of the core and shell to press the shell into holding engagement with the socket, a slot in said core, and a projection on said shell extending into said slot for limiting the relative rotary movement of said shell and core.

20. In an electrical connecting device, a plug adapted to be inserted into a socket and comprising a core having a plurality of circumferential cam faces and depressions extending lengthwise of the core, an expansible shell surrounding the core, and bearing members on said shell which engage the cam faces for expanding the shell when the shell is turned relatively to said core and which enter into said depressions when the shell is contracted.

21. In an electrical connecting device, a

- plug adapted to be inserted into a socket and comprising a core having a plurality of circumferential cam faces and depressions extending lengthwise of the core between the cam faces, an expansible shell surrounding the core, and bearing members secured to said shell and adapted to enter into said depressions, said bearing members engaging said cam faces and causing the shell to be expanded by relative rotation of the shell and core, and means on said core to prevent endwise movement of the shell on the core.
22. In an electrical connecting device, a plug adapted to be inserted into a socket and comprising a core having a plurality of circumferential cam faces and depressions extending lengthwise of the core between the cam faces, an expansible shell surrounding the core, and bearing members secured to said shell and adapted to enter into said depressions, said bearing members engaging said cam faces and causing the shell to be expanded by relative rotation of the shell and core, and means for limiting the rotary motion of said shell relatively to said core to prevent the bearing members from moving through a distance greater than the circumferential length of one cam face and one of said depressions.
23. In an electrical connecting device, a plug adapted to be inserted into a socket and comprising a core having a plurality of circumferential cam faces and depressions extending lengthwise of the core between the cam faces, an expansible shell surrounding the core, and bearing members secured to said shell and adapted to enter into said depressions, said bearing members engaging
- said cam faces and causing the shell to be expanded by relative rotation of the shell and core, a circumferential groove in said core connecting with one of said depressions, and a projection on one of said bearing members adapted to enter said groove and to limit the rotary movement of said shell relatively to said core.
24. In an electrical connecting device, the combination of a plug adapted to be inserted into a socket and comprising a core, an expansible contact member mounted on said core and adapted to yieldingly engage the inner face of a socket when said plug is inserted endwise into said socket, and cooperating means on said core and said contact member actuated by turning said core for expanding said contact member into firm engagement with said socket.
25. The combination of a plug adapted to be inserted into a socket, and comprising a core, an expansible contact member mounted on said core and adapted to yieldingly and frictionally engage the inner face of said socket when said plug is inserted endwise into said socket whereby the core may be turned relatively to said frictionally held contact member, and cooperating means on said core and said contact member actuated by turning said core for expanding said contact member into firm engagement with said socket.

Witness my hand, this 29th day of October, 1915.
